SUPERHEATED STEAM COOLING DEVICE

Howard J. Kerr, Westfield, N. J., assignor to
The Babcock & Wilcox Company, Bayonne,
N. J., a corporation of New Jersey

Application July 22, 1930, Serial No. 469,657

11 Claims. (Cl. 122—479)

This invention relates to steam superheaters and more particularly to a device for regulating the temperature of superheated steam delivered from a superheater of a steam boiler.

5 An object of the invention is to provide a device to regulate the temperature of superheated steam and avoid overheating of the metal of the superheater.

Another object of the invention is to provide a 10 boiler which will deliver superheated steam at constant temperature independent of the quantity without damage to the superheater itself.

Other objects will be apparent to those skilled 15 in this particular art from the description in the specification in connection with the drawings, in which—

Fig. 1 is a side view of a portion of a boiler and its setting illustrating the invention with one arrangement of superheaters;

20 Fig. 2 is a side view of a portion of a boiler and its setting illustrating the invention with a second superheater arrangement;

Fig. 3 is a sectional plan view of the temperature 25 regulating part of the superheater in section;

Fig. 4 is a sectional end view of the temperature regulating part of the superheater taken along the section line 4—4 of Fig. 3;

Fig. 5 is a sectional side view of a portion of 30 the temperature regulating part of the superheater taken at right angles to Fig. 3;

Fig. 6 is a sectional end view of a modified form 35 of the temperature regulating part of the superheater; and

Fig. 7 is a somewhat diagrammatic view of the superheat regulator control system.

In the arrangement shown in Fig. 1 hot gases 40 of combustion from a furnace (not shown) pass first through a set of steam generating tubes 1 and then over the tubes of a secondary superheater 2. The tubes 1 serve a multiple purpose, for in addition to their generating function they limit the radiant heat received by the superheater and act as a slag screen to prevent the 45 closing of passages between the superheater tubes by slag. After passing through the secondary superheater tubes the hot gases of combustion pass over the tubes of a primary superheater 3 and finally, by virtue of the several baffling arrangements 4, the hot gases of combustion are directed 50 across the tubes 5 and 6 of the water tube boiler.

The front and middle steam and water drums 7 are connected along their lengths by water circulators 9 and steam circulators 9^a while the 55 middle and rear drums 7 are directly connected

by steam circulators 8 only. The steam generated in the boiler collects in the rear steam and water drum and is conducted to a saturated steam header 10 by means of delivery pipes 11. The saturated steam from the header 10 is delivered 5 to the bank of looped tubes in the upper portion of the first gas pass of the boiler constituting the primary superheater section 3 through tube portions 12 bent to pass between the circulators 9^a and 9 and steam generating tubes 5. Each of 10 the primary superheater tubes is arranged in a series of vertical legs connected at their upper and lower ends to the adjacent tube legs for a series steam flow therethrough. The primary superheater section is positioned in the upper part 15 of the first gas pass of the boiler within the space between the rows of generating tubes 1 and 5. The steam will flow in parallel through the bank of primary superheater tubes and be superheated by the heat absorbed from the combustion gases 20 contacting with the tubes after the gases have been partly cooled by their passage across the row of boiler tubes 1 and the secondary superheater tubes. The superheated steam is conducted from the primary superheater section through tube portions 14 to a cooler or superheat regulator 13. The primary superheater tubes being arranged 25 above the generating tubes 1 and the secondary superheater tubes will receive substantially all 30 of their heat from the combustion gases. The superheat temperature of the steam entering the regulator 13 will thus be dependent upon the amount and temperature of the combustion gases flowing across the primary superheater tubes, 35 and will normally vary over a substantial range with changes in the rate of operation of the boiler.

The superheat regulator 13 comprises a cylindrical casing 21 having heads 22 and 23 secured to opposite ends thereof. A pair of longitudinally 40 extending side partitions 34 and an intermediate center baffle 35 unite with circular transverse partitions 23^a and 23^b to define a pair of side-by-side compartments extending longitudinally of the casing 21 and connected for a serial flow of steam 45 therethrough over the upper end of the center baffle 35. A bank of nested U-shaped tubes 30 having spaced tube legs 15 and 16 are arranged longitudinally of the casing 21 with the tube legs 15 arranged in horizontal and vertical rows in 50 one compartment and the tube legs 16 similarly arranged in the other compartment. The tube portions 14 open along the bottom of the compartment containing the tube legs 15 so that the superheated steam will flow upwardly across the 55 tube legs 15, over the baffle 35, and downwardly

across the tube legs 16. Tube portions 17 leading to the secondary superheater section 2 open along the length of the chamber containing the tube legs 16 similar to the arrangement of the tube portions 14, so that flow paths of uniform length having substantially similar heat transfer relations with the regulator tubes are formed between corresponding tube portions 14 and 17.

The tube legs 16 are connected to a common inlet header 29 between the partition 23^b and the head 23, while the tube legs 15 are connected to a common outlet header 31 adjacent the header 29. A water inlet pipe 24 and an outlet pipe 25 are mounted in the head 23 by means of steam tight expansion sleeves 26 welded thereto. The regulator steam cooling water entering the pipe 24 passes into the header 29, through the tube legs 16 and 15 successively to the outlet header 31 and outlet pipe 25, with the steam to be desuperheated passing through the regulator counter-current to and out of contact with the cooling water. Metallic fins 32 are mounted on the regulator tube legs 15 and 16 in good thermal contact therewith to add to the effectiveness of heat transfer from the superheated steam to the cooling water.

The regulator cooling water may be derived from any convenient source, and water from one of the steam and water drums 1 may be used. In the latter case, the regulator water will enter at the saturated steam temperature, and the heat absorbed in desuperheating will result in the evaporation of some or all of the regulator water, depending upon the amounts of water introduced and heat absorbed. Saturated steam or a mixture of steam and water will then be discharged from the outlet pipe 25.

The desuperheating effect of the regulator on the superheated steam from the primary superheater section will depend upon the amount of water supplied to the inlet pipe 24. A suitable flow regulating means, such as a control valve 27, is incorporated in the inlet pipe 24. By means of the control device 27, the supply of cooling water to the regulator may be regulated even to zero.

The desuperheated steam leaves the regulator through the tube portions 17 to the bank of looped tubes constituting the secondary superheater section 2. These tubes have a series of horizontally inclined superposed parallel tube legs connected by loops for a series flow therethrough and arranged across the lower part of the tapering first gas pass between the single row of boiler tubes 1 and the generating tubes 5, and in operation absorb heat from the high temperature combustion gases leaving the furnace and by radiation from the furnace. The secondary superheater tubes are arranged in pairs with their looped portions nested as shown in Fig. 1. While the lower portions of the tubes 4 restrict the amount of radiant heat from the furnace to the secondary superheater tubes to prevent overheating, these superheater tubes will receive a substantial amount of radiant heat through the spaces between the subjacent tubes 1. The steam is superheated to the desired final temperature in the secondary section and is conducted by tube portions 18 to an external steam outlet header 19. Due to the relatively large amount of radiant heat received by the secondary superheater tubes from the furnace, fluctuations in boiler load will have relatively little effect on the amount of superheat obtained in the secondary section as compared with the variations in superheat temperature in the

primary section. The tube portions 14, 17 and 18 are bent similarly to the tube portions 12 to pass between the generating tubes 5 and circulators 9.

Fig. 2 shows a modified steam boiler having the same general construction and arrangement of the steam generating and superheating parts as the boiler shown in Fig. 1, differing therefrom mainly in the particular formation of the tubes forming the primary and secondary superheater sections. In Fig. 2 the secondary superheater tube legs below the primary superheater are more horizontal than in Fig. 1 and have the tube portions connected to the superheat regulator casing and outlet header 19 extending along opposite sides of the primary superheater section.

Fig. 6 shows a modification of the regulator 13 wherein the steam from the primary superheater is directed in a single pass across the cooling tubes 30, but also counter-current to the flow of water therein.

In boilers of this nature, as the quantity of steam used increases or decreases the temperature of the steam taken therefrom often increases or decreases within undesirably large ranges. With this device it is obviously possible to control the temperature of the steam independently of the quantity used.

The steam from the boiler is superheated in two stages—first, in the primary superheater 3, then in the secondary superheater 2, with a regulator between these two stages and in its passage through the regulator it is normally cooled to an extent sufficient to maintain the outlet steam temperature constant, the amount of interstage cooling being regulated by the water supply through the control valve 27. When the conditions of boiler operation are such as to make the superheated steam delivery to be at too high a temperature more water is admitted to the regulator so as to lower the temperature of the steam entering the secondary superheater. Contrariwise, a decreased supply of water is used when the superheated steam temperature is too low. It will be clear that with this method of regulating the temperature of the delivered steam there is a corresponding regulation of the temperature of the metal of the superheater which obviously cannot become so hot as to be damaged so long as the outlet temperature of the superheated steam emerging from it is kept within the desired limits. While water is a convenient and desirable cooling medium other media may be used in the regulator without departing from my invention.

While a manually operated valve 27 is illustrated for control of cooling fluid to regulate outlet steam temperature it is to be understood that automatic thermostatic control of the water supply may be used and actuated by outlet temperature of the superheated steam leaving the secondary superheater section. Suitable automatic thermo-responsive control means adapted for such use are well known and, as somewhat diagrammatically illustrated in Fig. 7, comprise a thermostatically controlled valve 27' in the inlet pipe 24, the position of which valve is controlled by a thermostat 40 installed in the steam outlet header 19 and directly actuating the valve 27' through the volumetric changes of the volatile liquid in the thermostat and flexible pipe connection 41 to the valve 27' in response to steam outlet temperature changes.

Although certain features of the present invention

tion have been described in more or less detail, it will be apparent that various changes, additions, omissions, and substitutions can be made therein without departing from the spirit of this 5 invention and the scope of the appended claims.

I claim:

1. A steam generator having a combustion chamber, a multiplicity of steam generating elements arranged above said combustion chamber, a steam and water drum connected to said steam generating elements, a plurality of primary superheating tubes arranged to receive all of the steam to be superheated from said steam and water drum, a plurality of secondary superheating tubes in series with said primary superheating tubes and arranged for exposure in operation to heating gases at a temperature different from the temperature of the heating gases contacting with said primary superheating tubes, a regulable desuperheater arranged to receive the steam from said primary superheating tubes and comprising cooling tubes for cooling the steam before delivery to said secondary superheating tubes, corresponding primary and secondary superheating tubes being similarly connected to said desuperheater and so arranged relative to said desuperheater cooling tubes as to form substantially individual flow paths of uniform length in said desuperheater having substantially similar heat transfer relations with said cooling tubes, whereby all of the steam will be subjected to substantially uniform cooling in said desuperheater and the metal temperature conditions in said secondary superheating tubes will be substantially uniform in operation.

2. In a steam generator having a combustion chamber, a multiplicity of steam generating elements arranged to absorb heat from the heating gases leaving said combustion chamber, and a steam and water drum connected to the steam generating elements, the combination with a primary steam superheater arranged to receive all of the steam to be superheated from said steam and water drum and including an outlet header and a plurality of superheating tubes connected at points substantially throughout the length of said outlet header and providing parallel steam flow paths between said steam and water drum and outlet header, a secondary superheater including a plurality of superheating tubes arranged in parallel and exposed in operation to different heating gas temperatures than the tubes of said primary superheater and connected to said outlet header at points substantially throughout the length thereof and equispaced from the points of connection of the corresponding primary superheating tubes and so forming steam flow paths therein of uniform length between corresponding primary and secondary superheating tubes, and cooling fluid conduits extending longitudinally in said outlet header and transversely of said steam flow paths for substantially uniformly cooling all of the steam passing to the tubes of said secondary superheater, whereby the steam superheating capacity of all of the tubes of said secondary superheater may be fully utilized without exceeding the permissible metal temperatures therein.

3. Apparatus of the character described comprising, in combination, a boiler, a first superheater section located in the boiler so as to absorb heat substantially by convection, a second superheater section located in a zone of intense heat and so as to absorb heat substantially by

radiation, a conduit for conducting saturated steam from the boiler to said first section, a controllable superheat regulator arranged to receive steam from said first section and to deliver to said second section all the steam to be superheated therein, said regulator comprising means providing a substantially uniform path of flow for steam passing through the regulator and a space for cooling water out of contact with, but in heat exchange relation to, the steam flowing through said path, and means responsive to the temperature of steam which has received additional superheat in said second section for controlling said regulator.

4. In the art of superheating steam to high temperatures, the improved method which consists in initially superheating saturated steam by convection in a zone of relatively low temperature, regulating the temperature of the initially superheated steam by uniformly subjecting said initially superheated steam to the cooling effect of water out of contact therewith, subsequently superheating the steam to desired final temperature in a zone of intense radiant heat and governing the regulated temperature of the initially superheated steam in response to variations in temperature of steam which has been superheated in said second mentioned zone.

5. Apparatus of the character described comprising, in combination, a boiler, a first superheater section, a second superheater section, said sections being located in different heating zones in the boiler and said first section being located in a zone in which the variation in the amount of superheat obtained during normal operation of the boiler is greater than in the zone in which said second section is located, a superheat regulator, a conduit for conducting saturated steam from the boiler to said first section, a conduit for conducting steam from said first section to said regulator, a conduit for conducting from said regulator to said second section all of the steam to be superheated therein, said regulator comprising means providing a path of flow for steam through the regulator and a space for water to be evaporated by steam flowing through said path out of contact with the water, and means responsive to the temperature of steam on the discharge side of said regulator for controlling operation of the regulator.

6. Apparatus of the character described comprising, in combination, a boiler, a first superheater section, a second superheater section, said sections being serially arranged with respect to gas flow through the boiler and said second section being located in a zone of intense gas temperature where the difference in the amount of superheat obtained is less at different rates of boiler operation than is the difference in the amount of superheat obtained in said first section at different rates of boiler operation, a superheat regulator, a conduit for conducting saturated steam from the boiler to said first section, a conduit for conducting steam from said first section to said regulator, a conduit for conducting from said regulator to said second section all of the steam to be superheated therein, said regulator comprising means providing a path of flow for steam through the regulator and a space for water to be evaporated by steam flowing through said path out of contact with the water, and means responsive to the temperature of steam on the discharge side of said regulator for controlling operation of the regulator.

7. Apparatus of the character described comprising, in combination, a boiler, a first superheater section located in the boiler so as to absorb heat substantially by convection, a second superheater section located in a zone of intense heat and so as to absorb heat substantially by radiation, a superheat regulator, a conduit for conducting saturated steam from the boiler to said first section, a conduit for conducting steam from said first section to said regulator, a conduit for conducting from said regulator to said second section all of the steam to be superheated therein, said regulator comprising means providing a substantially uniform path of flow for steam passing through the regulator and a space for water to be evaporated by steam flowing through said path out of contact with the water, and means responsive to the temperature of steam which has received additional superheat in said second section for controlling said regulator.

8. Apparatus of the character described comprising, in combination, a boiler, a first superheater section, a second superheater section, said sections being located in different heating zones in the boiler and said first section being located in a zone in which the variation in the amount of superheat obtained during normal operation of the boiler is greater than in the zone in which said second section is located, a superheat regulator, a conduit for conducting saturated steam from the boiler to said first section, a conduit for conducting steam from said first section to said regulator, a conduit for conducting from said regulator to said second section all of the steam to be superheated therein, said regulator comprising means providing a path of flow for steam through the regulator and a space for water to be evaporated by steam flowing through said path out of contact with the water, a conduit for supplying water to said space from the boiler, and means responsive to the temperature of steam on the discharge side of said regulator for controlling operation of the regulator.

45 9. In the art of superheating steam to high temperatures in a boiler setting, the improved method which consists in initially superheating saturated steam by convection in a zone of relatively low temperatures, whereby the temperature of the initially superheated steam tends to

vary with variations in rate of operation of the boiler, regulating the temperature of the initially superheated steam by evaporating water out of contact therewith, subsequently superheating the steam to desired final temperature in a zone of intense radiant heat and governing the regulated temperature of the initially superheated steam in response to variations in temperature of steam which has been superheated in said second mentioned zone. 10

10 10. In the art of superheating steam to high temperatures, the improved method which consists in initially superheating saturated steam in a first zone, regulating the temperature of the initially superheated steam by passing the same in heat exchange relation and out of contact with water at substantially the vaporizing temperature corresponding to the pressure of the water, whereby to desuperheat the steam by evaporating water, subsequently superheating the steam in a second zone of materially higher temperature than said first mentioned zone and tending to impart to the steam a relatively constant amount of superheat as compared with the amount of superheat imparted in said first mentioned zone and regulating the amount of desuperheating in response to variation in temperature of steam leaving said second zone to provide a supply of superheated steam of substantially constant temperature entering said second zone. 20 25

11. The improved method of operating a superheating boiler to provide superheated steam at high temperature which consists in initially superheating saturated steam in a first zone in the boiler, withdrawing water from the boiler and passing the same in heat exchange relation and out of contact with the initially superheated steam to regulate the temperature of the initially superheated steam by causing the steam to evaporate some of said water and subsequently adding additional superheat to the desuperheated steam in a second zone of intense heat in said boiler in advance of said first mentioned zone with respect to flow of combustion gases through the boiler and tending to impart to the steam a relatively constant amount of superheat as compared with the amount of superheat imparted in said first mentioned zone. 30 35 40 45
